UNITED STATES PATENT OFFICE.

EDGAR D. MARTIN, OF CHICAGO, ILLINOIS.

SYSTEM OF INTEGRALLY-CAST REINFORCED-CONCRETE ROOF CONSTRUCTION FOR BUILDINGS.

1,411,446.

Specification of Letters Patent.

Patented Apr. 4, 1922.

Application filed March 14, 1921. Serial No. 452,144.

To all whom it may concern:

Be it known that I, EDGAR D. MARTIN, a citizen of the United States, and a resident of Chicago, Cook County, and State of Illinois, have invented certain new and useful Improvements in a System of Integrally-Cast Reinforced-Concrete Roof Construction for Buildings, of which the following is declared to be a full, clear, and exact description.

This invention relates to a system of integrally cast reinforced concrete pitched roof construction for buildings, and its principal object is to provide an improved reinforced concrete roof construction suitable for spans as great as eighty feet or over, in which a multiplicity of carrying members is obviated. Another object is to obtain greater economy, simplicity, lightness, strength, durability and rigidity in the construction of roof structures. Another object is to provide such a roof structure with facilities for lighting and ventilating purposes.

With these and other objects and advantages in view, this invention consists in a reinforced concrete roof construction, having oppositely inclined members, diverging from a common support and sloping upward and outward, in which oppositely inclined roof members are restrained one to the other by metal ties. It further consists in a reinforced concrete roof in which the oppositely inclined roof members are restrained one to the other, and suspend, from their outer upper ends, other roof members. It further consists in the several novel features herein-after fully set forth and claimed.

The invention is clearly illustrated in the drawings accompanying this specification, in which:

Fig. 1 is a cross section through a roof construction, embodying a simple form of the present invention; Fig. 2 is a plan of a fragment thereof; Fig. 3 is a detail fragmental vertical section taken on line 3—3 of Fig. 2; Fig. 4 is a detail cross section taken on line 4—4 of Fig. 1; Fig. 5 is a vertical cross section of a roof construction illustrating a slightly modified form of the invention; Fig. 6 is a vertical cross section illustrating the application of the invention to a long span roof having supports intermediate its ends and Fig. 7 is a vertical cross section illustrating an application of a slightly modified

form of the invention to a long span roof having supports intermediate its ends.

Referring to said drawings, and first to Figs. 1 to 4 inclusive, the reference character 10 designates supports such as the columns or walls of a building, and said columns or walls may be constructed of reinforced concrete, masonry or structural iron work, etc., as is desired.

The roof 11, comprises a series of successively arranged, statically rigid, metal reinforced, oppositely inclined, intersecting ribs 13, that have oppositely inclined members 14, beyond the intersecting places that slope upward and outward from their support on the main members or ribs 13 and are restrained one to the other, at their outer upper ends by tie rods 15.

The structures 12 are connected at their outer, lower ends by lateral girders 9 and are supported by the columns or walls 10. They are restrained from spreading apart by tie rods 16 that connect their lower outer ends.

The roof covering may comprise an upper roof slab 17 and two lower roof slabs 18 which are spaced away from the upper roof slab to leave free space 19 for lighting and ventilating purposes.

The upper roof slab 17 may take the form of a catenary suspended generally from longitudinal ribs 20 that extend between and connect the outer upper ends of the roof members 14. The lower roof slabs may extend from the supports 10 part way up the ribs 13. At the inner edge portions of the lower roof slabs 18 are thickened portions 21 which act as longitudinal girders, and extending between and connecting the upper outer ends of the upper roof members 14 and lower roof members 13 at the girders 21 are suspending members 22, in the form of bars or rods, that carry, in part, the load of the lower roof slabs, and resist any tendency for the ribs or lower roof members 13, to deflect or bend downwards between their ends. The roof slabs and ribs are metal reinforced, as is well understood and all are cast integrally, forming a unified mass.

The advantages of a roof constructed in accordance with the above description are readily apparent. The downwardly curved roof slab being supported by the longitudinal ribs, it supports the roof load by direct

tension instead of transversely, and being supported by the longitudinal ribs, the load is transferred by the upper roof members 14 by direct compression to the apex or place of intersection of the inclined members. The roof slab may be made much lighter than heretofore and therefore it reduces the loads carried by the upper roof members 14 and consequently by the lower roof members 13 and lower tie rods 16. The horizontal pull of the catenary slab acts opposite to the spreading stress of the upper roof members 14, which is taken up by the tie rods 15, thereby reducing the stress in said tie rods and permitting of the use of lighter and less material.

In the modified form illustrated in Fig. 5, the construction is substantially the same as that illustrated in Fig. 1, except that in place of making the upper roof slab in the form of a catenary curve, the roof slab 17^a may run parallel with the upper roof members 14, forming two diverging upwardly sloping roof slab sections. The tie rods 15 relieve the upper roof members 14 from transverse action, and the load carried by the longitudinal ribs 20 is transferred by direct compression to the apex or intersecting place of the inclined roof members. In this case, a longitudinal rib 20^a at the apex may be added to give additional rigidity to the structure.

In both forms, the suspending members 22 relieve the inclined members 13 from the transverse action of the lower roof slabs 18 and carry it to the upper roof members 14 which carry it by direct compression to the apex or intersecting place of the inclined members from which it is transferred by direct compression to the columns or walls. This permits long spans to be carried with a minimum of materials and affords a substantial, rigid and well lighted and ventilated roof in which the inclined roof structures 12 of the series may be widely spaced one from the other.

In Fig. 6 is shown a roof construction consisting of a plurality of conterminous roof constructions, of the form illustrated in Fig. 2 and described in connection therewith. Each series of columns 10^b forms the support for two adjacent roof constructions. In this case the tie rods 16^b may run between the girders 21^b, thus tying the inclined roof members 12^b together intermediate their ends, in place of at their lower ends, as in the form illustrated in Fig. 2. The upper and lower roof slabs 17^b and 18^b and ties 15^b, 22^b are employed as in the forms heretofore described.

In accordance with one phase of the invention, the upper roof portions, without the lower ones, may be employed to form an extended roof. In Fig. 7 such a construction is illustrated and forms a sort of

"saw tooth" shaped roof. In this application of the invention the roof structure is supported by columns or other supports 10^c. The oppositely inclined and diverging roof members 14^c, 14^d, take their support on the columns 10^c and are tied together at their upper outer ends by tie rods 15^c. Lower tie rods 16^c connect the lower ends of the roof members. Between the directly supported roof members, 14^c, 14^d, are intermediate inclined roof members 14^e that run parallel with the inclined roof members 14^c, the lower ends of which are connected to the upper ends of adjacent roof member 14^c by inclined ties or sustaining members 14^f. The lower tie rods 16^c tie the lower ends of the members 14^c, 14^d, to the lower ends of the roof members 14^c, 14^d and to the columns 10^c. In this form of the invention, the roof members 14^c, 14^d, may have less slope than the members 14^e, 14^f, and may have roof slabs 17^c cast thereon. Openings are left in the roof members 14^c, 14^d to afford spaces for lighting and ventilating purposes.

I claim as new and desire to secure by letters patent:

1. A system of reenforced concrete roof construction, comprising a series of successively arranged, statically rigid, metal reenforced concrete structures, cast integrally and forming a unified mass, and having oppositely inclined members diverging from their support and sloping upward and outward and restrained one to the other near their outer and upper ends by metal ties.

2. A system of reenforced concrete roof construction, comprising a series of successively arranged, statically rigid, metal reenforced concrete structures, cast integrally and forming a unified mass, in which oppositely inclined members, diverging from their support and sloping upward and outward, are restrained one to the other near their outer and upper ends by metal ties and a roof slab supported from said oppositely inclined members.

3. A system of reenforced concrete roof construction, comprising a series of successively arranged, statically rigid metal reenforced concrete structures, cast integrally and forming a unified mass, in which oppositely inclined members, diverging from their support and sloping upward and outward, are restrained one to the other near their outer and upper ends by metal ties, and a roof slab cast integrally with said oppositely inclined members.

4. A system of reenforced concrete roof construction, comprising a series of successively arranged, statically rigid metal reenforced concrete structures, cast integrally and forming a unified mass, in which oppositely inclined members, diverging from their support and sloping upward and out-

ward, are restrained one to the other near their outer and upper ends by metal ties, and a downwardly curved roof slab supported from said oppositely inclined 5 members.

5. A system of reenforced concrete roof construction, comprising a series of successively arranged, statically rigid, metal re-enforced concrete structures, cast integrally 10 and forming a unified mass, and having oppositely inclined members diverging from their support and sloping upward and outward and restrained one to the other near their outer and upper ends by metal ties, 15 and suspension members secured to the upper, outer ends of said oppositely inclined members.

6. A system of reenforced concrete roof construction, comprising a series of successively arranged, statically rigid, metal re-enforced concrete structures, cast integrally 20 and forming a unified mass, in which oppositely inclined members, diverging from their support and sloping upward and outward, are restrained one to the other near their outer and upper ends by metal ties, a roof slab cast integrally with said oppositely inclined members, and suspension members secured to the outer, upper ends of said oppositely inclined members for suspending 25 roof members therebelow.

7. A system of reenforced concrete roof construction, comprising a series of successively arranged, statically rigid, metal re-enforced concrete structures, consisting of oppositely inclined members that intersect each other, and supports therefor at their lower ends in combination with an upper roof slab supported above the intersections by the portions 30 of the intersecting members which extend beyond the intersection, said intersecting members being restrained one to the other at their upper and outer ends by metal ties, and lower roof slabs adjacent 45 said supports, the whole being cast integrally with each other and forming a unified mass.

8. A system of reenforced concrete roof construction, comprising a series of successively arranged, statically rigid, metal re-enforced concrete structures, consisting of oppositely inclined members that intersect each other, and supports therefor at their lower ends, in combination with an upper downwardly curved roof slab supported 50 above the intersections by the portions of the intersecting members which extend beyond the intersections, said intersecting members being restrained one to the other at their upper and outer ends by metal ties, 55 and lower roof slabs adjacent said supports, the whole being cast integrally with each other and forming a unified mass.

9. A system of reenforced concrete roof construction, comprising a series of successively arranged, statically rigid, metal reen-

forced concrete structures, consisting of oppositely inclined members that intersect each other, and supports therefor at their lower ends, in combination with an upper roof slab supported above the intersections by the portions 70 of the intersecting members which extend beyond the intersections, said intersecting members being restrained one to the other at their upper and outer ends by metal ties, and lower roof slabs adjacent said supports, the whole being cast integrally with each other and forming a unified mass.

10. A system of reenforced concrete roof construction, comprising a series of successively arranged, statically rigid, metal re-enforced, concrete structures, consisting of opposing, inclined members that intersect each other, which are conterminous and integral at the points of intersection, and supports therefor at their lower ends, in combination with upper roof slabs, supported above the intersections by the portions of the intersecting members which extend beyond 75 the intersections, said intersecting members being restrained one to the other at their outer upper ends by metal ties, and lower roof slabs adjacent said supports, the whole being cast integrally with each other and forming a unified mass.

11. A system of reenforced concrete roof construction, comprising a plurality of a conterminous series of successively arranged, statically rigid, metal reenforced, concrete 80 structures, consisting of opposing, inclined, members that intersect each other, and supports therefor at their lower ends, in combination with upper roof slabs, supported above the intersections by the portions of the intersecting members which extend beyond 85 the intersections, said intersecting members being restrained one to the other at their outer upper ends by metal ties, and lower roof slabs adjacent said supports, the whole being cast integrally with each other and forming a unified 90 mass.

12. A system of reenforced concrete roof construction, comprising a plurality of a conterminous series of successively arranged, statically rigid, metal reenforced, concrete 100 structures, consisting of opposing, inclined members that intersect each other, and supports therefor at their lower ends, in combination with upper roof slabs, supported above the intersections by the portions of the intersecting members which extend beyond 105 the intersections, said intersecting members being restrained one to the other at their outer upper ends by metal ties, and lower roof slabs adjacent said supports, the whole 110 being cast integrally with each other and forming a unified mass.

12. A system of reenforced concrete roof construction, comprising a plurality of a conterminous series of successively arranged, statically rigid, metal reenforced, concrete 115 structures, consisting of opposing, inclined members that intersect each other, and supports therefor at their lower ends, said intersecting members being conterminous and integral across said supports, in combination with upper roof slabs, supported above the intersections by the portions of the intersecting members which extend beyond the intersections, said intersecting members being restrained one to the other at their outer 120 upper ends by metal ties, and lower roof slabs adjacent said supports, the whole being cast integrally with each other and forming a unified 125 mass.

13. A system of reenforced concrete roof construction comprising a series of successively arranged, statically rigid, metal reenforced, concrete structures, consisting of opposing, inclined, members that intersect each other, and supports therefor at their lower ends, in combination with upper roof slabs, supported above the intersections by the portions of the intersecting members 10 which extend beyond the intersections, said intersecting members being restrained one to the other at their outer upper ends by metal ties, and lower roof slabs adjacent said supports, the whole being cast integrally and forming a unified mass, there being window 15 openings between the upper and lower roof slabs.

14. A system of reenforced concrete roof construction, comprising a series of statically rigid, metal reenforced, concrete structures, consisting of opposing, inclined members that intersect each other, supports therefor at their lower ends, and transverse restraining members, in combination with a 20 downwardly curved upper roof slab, supported above the intersections by the portions of the intersecting members which extend beyond the intersections, said intersecting members being restrained one to the other at their outer upper ends by metal ties, and lower roof slabs adjacent said supports, the whole being cast integrally and forming a unified mass.

15. A system of reenforced concrete roof construction, comprising a series of successively arranged, statically rigid, metal reenforced concrete structures, consisting of opposing, inclined members that intersect each other, and supports therefor at their lower 25 ends, and transversely extending tie rods, in combination with an upper roof slab, supported above the intersections by the portions of the intersecting members which extend beyond the intersections, said intersecting members being restrained one to the other at their outer upper ends by metal ties, and lower roof slabs adjacent said supports, the whole being cast integrally and forming a unified mass.

16. A system of reenforced concrete roof construction, comprising a series of successively arranged, statically rigid, metal reenforced concrete structures, consisting of opposing, inclined members that intersect each other, co-incident lateral restraining members therefor, and supports at said restraining members, in combination with an upper roof slab, supported above the intersections by the portions of the intersecting members 30 which extend beyond the intersections, said intersecting members being restrained one to the other at their outer upper ends by metal ties, and lower roof slabs adjacent said supports, the whole being cast integrally and forming a unified mass.

17. A system of reenforced concrete roof construction, comprising a series of successively arranged, statically rigid, metal reenforced, concrete structures, consisting of opposing, inclined members that intersect each other, co-incident lateral restraining members therefor, supports at said restraining members and tie rods connecting said restraining members, in combination with an upper roof slab, supported above the intersections by the portions of the intersecting members which extend beyond the intersections, said intersecting members being restrained one to the other at their outer upper ends by metal ties, and lower roof slabs 40 adjacent said supports, the whole being cast integrally and forming a unified mass.

18. A system of reenforced concrete roof construction, comprising a series of successively arranged, statically rigid, metal reenforced, concrete structures, consisting of opposing, inclined members that intersect each other, which are conterminous and integral at the points of intersection, and supports therefor at their lower ends, in combination with upper roof slabs, supported above the intersections by the portions of the intersecting members which extend beyond the intersections, said intersecting members being restrained one to the other at their outer 45 upper ends by metal ties, roof suspending members secured to and extending down from the upper outer ends of said intersecting members, and lower roof slabs adjacent 50 said supports suspended by said roof suspending members, the whole being cast integrally and forming a unified mass.

19. A system of reenforced concrete roof construction, comprising a plurality of a conterminous series of successively arranged, statically rigid, metal reenforced, concrete structures, consisting of opposing, inclined members that intersect each other, and supports therefor at their lower ends, in combination with upper roof slabs, supported above the intersections by the portions of the intersecting members which extend beyond the intersections, said intersecting members being restrained one to the other at their outer upper ends by metal ties, roof suspending members secured to and extending down from the upper outer ends of said intersecting members, and lower roof slabs adjacent 60 said supports suspended by said roof suspending member, the whole being cast integrally and forming a unified mass.

20. A system of reenforced concrete roof construction, comprising a plurality of a conterminous series of successively arranged, statically rigid, metal reenforced, concrete structures, consisting of opposing, inclined members that intersect each other, and supports therefor at their lower ends, said intersecting members being conterminous and 65

- integral across said supports, in combination with upper roof slabs, supported above the intersections by the portions of the intersecting members which extend beyond the intersections, said intersecting members being restrained one to the other at their outer upper ends by metal ties, roof suspending members secured to and extending down from the upper outer ends of said intersecting members, and lower roof slabs adjacent said supports suspended by said roof suspending members, the whole being cast integrally and forming a unified mass.
21. A system of reenforced concrete roof construction, comprising a series of successively arranged, statically rigid, metal reenforced, concrete structures, consisting of opposing, inclined, members that intersect each other, and supports therefor at their lower ends, in combination with upper roof slabs, supported above the intersections by the portions of the intersecting members which extend beyond the intersections, said intersecting members being restrained one to the other at their outer upper ends by metal ties, roof suspending members secured to and extending down from the upper outer ends of said intersecting members, and lower roof slabs adjacent said supports, suspended by said roof suspending members, the whole being cast integrally and forming a unified mass.
22. A system of reenforced concrete roof construction, comprising a series of statically rigid, metal reenforced, concrete structures, consisting of opposing, inclined members that intersect each other, supports thereof at their lower ends, and transverse restraining members, in combination with a downwardly curved upper roof slab, supported above the intersections by the portions of the intersecting members which extend beyond the intersections, said intersecting members being restrained one to the other at their outer upper ends by metal ties, roof suspending members secured to and extending down from the upper outer ends of said intersecting members, and lower roof slabs adjacent said supports, suspended by said roof suspending members, the whole being cast integrally and forming a unified mass.
23. A system of reenforced concrete roof construction, comprising a series of successively arranged, statically rigid, metal reenforced, concrete structures, consisting of opposing, inclined members that intersect each other, and supports therefor at their lower ends, and transversely extending tie rods, in combination with an upper roof slab, supported above the intersections by the portions of the intersecting members which extend beyond the intersections, said intersecting members being restrained one to the other at their outer upper ends by metal ties, roof suspending members secured to and extending down from the upper outer ends of said intersecting members, and lower roof slabs adjacent said supports, suspended by said roof suspending members, the whole being cast integrally and forming a unified mass.
24. A system of reenforced concrete roof construction, comprising a series of successively arranged, statically rigid, metal reenforced, concrete structures, consisting of opposing, inclined members that intersect each other, co-incident lateral restraining members therefor, and supports at said restraining members, in combination with an upper roof slab, supported above the intersections by the portions of the intersecting members which extend beyond the intersections, said intersecting members being restrained one to the other at their outer upper ends by metal ties, roof suspending members secured to and extending down from the upper outer ends of said intersecting members, and lower roof slabs adjacent said supports, suspended by said roof suspending members, the whole being cast integrally and forming a unified mass.
25. A system of reenforced concrete roof construction, comprising a series of successively arranged, statically rigid, metal reenforced, concrete structures, consisting of opposing, inclined members that intersect each other, co-incident lateral restraining members therefor, supports at said restraining members and tie rods connecting said restraining members, in combination with an upper roof slab, supported above the intersections by the portions of the intersecting members which extend beyond the intersections, said intersecting members being restrained one to the other at their outer upper ends by metal ties, roof suspending members secured to and extending down from the upper outer ends of said intersecting members, and lower roof slabs adjacent said supports, suspended by said roof suspending members, the whole being cast integrally and forming a unified mass.
